US00D592347S

(12) **United States Design Patent**
Trott et al.

(10) **Patent No.:** **US D592,347 S**
(45) **Date of Patent:** **** May 12, 2009**

(54) **LIGHTING DEVICE**

(75) Inventors: **Gary David Trott**, Morrisville, NC (US); **Paul Kenneth Pickard**, Morrisville, NC (US)

(73) Assignee: **Cree LED Lighting Solutions, Inc.**, Durham, NC (US)

(**) Term: **14 Years**

(21) Appl. No.: **29/324,484**

(22) Filed: **Sep. 12, 2008**

Related U.S. Application Data

(63) Continuation of application No. 29/279,583, filed on May 3, 2007, now abandoned.

(51) **LOC (9) Cl.** **26-05**

(52) **U.S. Cl.** **D26/74; D26/118**

(58) **Field of Classification Search** **D26/2, D26/24, 35, 61, 7, 72, 74-79, 81-92, 118, D26/122, 138; 362/147-148, 217-225, 132, 362/150, 260-263, 267, 283, 337, 347, 364, 362/404; 43/113; D23/372, 328, 385; D14/209; 52/98; D25/138; D10/111, 118**

CLAIM

The ornamental design for a lighting device, as shown and described.

DESCRIPTION

FIG. 1 is a corner perspective view of the lighting device in accordance with our new design;

FIG. 2 is a bottom view thereof; and,

FIG. 3 is a side perspective view thereof.

The portions of the drawings shown in broken lines represent environmental structure and form no part of the claimed design.
